MULTIBARREL CARBURETOR

George M. Bicknell, St. Louis, Mo., assignor to
 Carter Carburetor Corporation, St. Louis, Mo.,
 a corporation of Delaware

Application December 19, 1949, Serial No. 133,930

8 Claims. (Cl. 123—127)

1

This invention relates to carburetors for internal combustion engines and consists particularly in a novel type of multibarrel carburetor.

It has been observed that a plain tube carburetor having a venturi of sufficient size and capacity to supply the fuel requirements of an engine during wide open throttle high speed operation fails to develop sufficient suction during wide open throttle low speed operation.

An object of this invention is to produce a carburetor for internal combustion engines having two intake manifolds, in which the advantages of the large and small venturi may be combined. To achieve this object I provide a carburetor with two sets of mixing conduits, one for low and medium speed operation, and one to provide additional fuel for high speed operation, one of each set of mixing conduits communicating with each intake manifold.

A second object is to provide a carburetor of the type indicated above which will insure an adequate supply of fuel at all times to at least one high speed and one low speed mixture conduit.

A third object is to provide, in a carburetor of this type means for preventing opening of the high speed mixture conduits until the low-speed throttles have opened a predetermined amount and until the engine is thoroughly warmed up.

I achieve these objects by providing a carburetor of the above type having two separate fuel reservoirs, each feeding fuel to one low speed and one high speed mixture conduit; suction responsive means for controlling the high speed throttles, thermostatic means for regulating separate choke valves governing each set of mixture conduits and for preventing opening of the high speed throttles until the engine has warmed up, and additional mechanical means for preventing opening of the high speed throttles until the low speed throttles are opened a predetermined amount.

Further objects and advantages will appear from reading the specification in connection with the drawings, in which:

Fig. 1 is a plan view partially sectionalized of a four barrel carburetor made according to my invention;

Fig. 2 is a partial vertical section along the line 2—2 of Fig. 1;

Fig. 3 is a vertical section along the line 3—3 of Fig. 1;

Fig. 4 is an elevation of the throttle body assembly, taken normal to the throttle shaft;

Fig. 5 is a vertical section taken along the line 5—5 of Fig. 1;

Fig. 6 is a diagrammatic view of the invention.

2

Referring now to the drawing, the numeral 10 indicates a carburetor airhorn formed with separate air inlets 11 and 13 separated by partition 14, and admitting air, respectively, to primary mixture conduits 16 and 17, and secondary mixture conduits 18 and 19.

Mixture conduits 16, 17, 18 and 19, respectively contain a series of coaxial venturis 15, the smaller of which are suspended from the mixture conduit walls by ribs 21 and 24.

Thermostatically-controlled unbalanced choke valves 22 and 23 in air inlets 11 and 13 regulate the admission of air into primary mixture conduits 16 and 17, and secondary mixture conduits 18 and 19, respectively. Choke valves 22 and 23 are separately mounted on parallel shafts 25 and 26 which are rotatably journaled in the air inlet walls. Operation of choke valves 22 and 23 is controlled by conventional thermostatic automatic choke control devices 27 and 27a.

The lower, or outlet portion of mixture conduits 16, 17, 18 and 19 is formed in throttle body casting 28. The outlets of primary mixture conduits 16 and 17 are controlled by throttle valves 29 mounted on shaft 30; throttle valves 31 mounted on parallel shaft 32, control the outlet of secondary mixture conduits 18 and 19. Throttle shafts 30 and 32 are rotatably journaled in the walls of throttle body casting 28, which is flanged at its lower end as at 34 for attachment to the intake manifolds 35 and 36.

Adjacent mixture conduits 16 and 18, and 17 and 19, respectively, are formed narrow constant level fuel reservoirs 37 and 38, containing floats 39, operating independently needle valves 40. Liquid fuel is admitted to the carburetor through fuel inlet 41 and passes through horizontal passageways 42 formed in rib structures 43 to needle valve 40 and therethrough into reservoirs 37 and 38. Reservoirs 37 and 38 are not connected at any point but communicate independently with the atmosphere in air horn 10 through passages 44 formed in wall structure 45.

The main fuel supply for primary mixture conduits 16 and 17 passes through main metering orifices 46 located in the bottom of reservoirs 37 and 38. Best disclosed in Fig. 5 horizontal passageways 47 connect orifices 46 with vertical passages 48 which extend upwardly through rib structures 49 formed on the inside wall of primary mixture conduits 16 and 17. Inclined passages 50 formed in ribs 21, and nozzles 51 carry the fuel into the center of the smallest venturi 15 of primary conduits 16 and 17 for discharge thereinto by induction. Air bleed passages 52 formed in ribs 21 connect passages 48 and nozzles 51.

Fuel for idling is provided to primary mixture conduits 16 and 17, only, through restricted tubes 54, which communicate at their lower end with passages 48 and at their upper end with horizontal passages 55, which, in turn, connect with vertical passages 57 leading to idle ports 58.

The effective area of metering orifices 46 is regulated by stepped metering pins 60, which are detachably secured at their upper ends to piston rods 61 for vertical movement therewith. Vertical movement is imparted to piston rod 61 by suction piston 63 which is slidably mounted in cylinder 64 forming part of the fuel reservoir wall structure. Passageway 65 and associated passages (not shown) connect cylinder 64 with primary mixture conduits 16 and 17 posterior to the throttle, so that movements of metering pins 60 are partly responsive to suction.

For additional control of metering pins 60, directly responsive to throttle movement, countershaft 66 is provided. Countershaft 66 is journaled in the wall structure of air horn 10, which also includes cover 67 for fuel reservoirs 37 and 38 and raised enclosure 68 thereon for the metering pin operating means. Adjacent the ends of countershaft 66 metering pin operating arms 70 are secured, the outer end 71 of operating arms 70 extending through a vertical slot 72 in piston rod 61 and adapted to engage the upper edge of said slot for the purpose of raising the metering pins. A crank 74 is secured to the end of countershaft 66 and is connected at its outer end by a suitable link 75 to an arm 77 secured at one end of throttle shaft 30, for rotational movement therewith, so that any movement of throttle shaft 30 is transmitted via arm 77, link 75, crank 74, countershaft 66 and arms 70 to metering pins 60, opening movements of primary throttles 29 tending to elevate metering pins 60, and throttle closing movements permitting pin 60 to drop. Covers 78, sealingly secured to raised enclosures 68, complete the enclosure of the metering pin operating means and thus prevent their fouling by dust particles, grease and dirt.

Additional fuel increments for acceleration are forced into primary mixture conduits 16 and 17 by a pump comprising a boss 79 formed integral with the mixture conduit wall structure, a diaphragm 80 sealingly secured against boss 79 by a cup 81. Spring 82, seated in cup 81 normally urges stem 84 of diaphragm 80 toward primary throttle shaft 30, which is formed with a flat-bottomed notch 85 at the point of intersection, a ball 86 being interposed between stem 84 and throttle shaft 30 to provide a rolling contact therebetween. Pumping chamber 88 communicates with fuel reservoirs 37 and 38 via inlet passage 90, and with pump nozzles 92 and 93 via passage 95 and outlet check valve 96. Notch 85 in throttle shaft 30 is so positioned that opening movements of throttle shaft 30 urge ball 86, stem 84, and diaphragm 80 outwardly, therefore discharging fuel from primary chamber 88.

The main fuel supply for secondary mixture conduits 18 and 19 passes through restricted orifices 98 one of which is located in each fuel reservoir. Vertical passages 99 extend upwardly and connect metering orifices 98 with inclined passages 103 formed in ribs 21. Fuel is carried by nozzles 104 into the center of the smallest venturis 15 of secondary mixture conduits 18 and 19.

Primary throttles 29 are controlled by the accelerator pedal through conventional linkages (not shown) pivotally connected near the outer

extremity of throttle operating arm 106, which is secured to an end of primary throttle shaft 30.

An arm 109 is secured to the opposite end of secondary throttle shaft 32 and is formed with an inwardly extending projection 110 for limiting closing movement of the throttle by bearing against throttle adjusting screw 112 when secondary throttle valves 31 are nearly closed; a second inwardly extending projection 113, the function of which will be explained in detail below; and, substantially intermediate of projections 110 and 113, a substantially radially extending cam element 114.

A boot shaped extension 116 having an arcuate end portion 117 concentric with throttle shaft 30 is formed on arm 77 of primary throttle shaft 30 and is adapted, as primary throttles 29 move toward closed position to contact cam 114, thereby urging secondary throttles 31 toward closed position.

A crank 118 is rotatably journaled on secondary throttle shaft 32 and is normally urged into abutting relation with projection 113 of arm 109 by torsion spring 119 so that rotary movements of arm 119 are transmitted to secondary throttle shaft 32; arm 118 is rotated clockwise (Fig. 3) by suction actuated bellows 120 which communicates with primary mixture conduits 16 at 122 through tubular passage 123. One end of bellows 120 is fixed with relation to the carburetor structure and the other, movable end is connected by a suitable link 124 with the outer end of crank 118, so that under predetermined high suction conditions in primary mixture conduits 16 and 17, when primary throttles 29 are sufficiently opened to move boot-like extension 116 away from cam 114, bellows 120 draws arms 118 and 109, and secondary throttles 31 toward open position. When secondary throttles 31 reach their fully opened position, further opening movement is prevented by cooperating stop lugs 122 and 122a, formed respectively on crank 118 and throttle body casting 28. A spring 121, secured at one end to crank 118 and at its other end to the carburetor normally urges crank 118 counterclockwise and throttles 31 closed, in opposition to the opening effect of bellows 120. When primary throttles 29 are closed, arcuate surface 117 of primary throttle shaft arm 77 bears against cam 114 of secondary throttle arm 109, thereby preventing further opening movement of arm 109 and secondary throttles 31, any movement of crank 118 being absorbed by torsion spring 119. For preventing opening of secondary throttles 31 until the engine has warmed up, thermostatically controlled bleeder valve 125 is interposed in the suction line 123 connecting bellows 120 and mixture conduits 16 and 17. Valve 125 is provided with a needle type closure member 126 slidably mounted in tubular guide 127 and has an extension 128; an arm 130, rigidly secured at one end to choke shaft 26 is connected at its other end to extension 128 by link 129 so that closing movement of choke shaft 26, caused by thermostatic choke control 27a elevates closure member 126 and consequently, when the engine is cold, and until it becomes heated, bellows 120 is vented to atmosphere, and secondary throttles 31 remain closed.

Fig. 6 diagrammatically illustrates the manner in which the primary and secondary mixture conduits are connected to the separate intake manifolds 35 and 36, primary mixture conduit 16 and secondary mixture conduit 18 feeding manifold 35; primary mixture conduit 17 and secondary mixture conduit 19 feeding manifold 36.

Operation of the carburetor is as follows: During idling, fuel is supplied to primary mixture conduits 16 and 17 from fuel chambers 37 and 38 via passages 57 and idle ports 58. As the operator depresses the accelerator pedal (not shown), primary throttle valves 29 are moved toward opened position, and throttle opening movement is transmitted by arm 77, link 75, crank 74, shaft 66, and metering pin operating arms 70 to raise metering pins 60, thus increasing the effective area of metering orifices 46 in proportion to the degree of throttle opening. As manifold suction decreases below a predetermined value, a spring (not shown) urges piston 63, rod 61, and metering pins 60 upwardly, thus providing additional fuel to the primary mixture conduits 16 and 17 in proportion to decreased manifold suction. Additional increments of fuel are discharged into primary mixture conduits 16 and 17 only during acceleration by accelerating pump 79-88 through nozzles 92. Thus, sufficient metered fuel is provided to the primary mixing conduits 16 and 17 and through them to intake manifolds 35 and 36 for part throttle operation. During this period the arcuate extension 116 on primary throttle operating arm 77 contacts cam 114 on secondary throttle operating arm 109, to lock secondary throttles 31 in the closed position. Since no manifold vacuum is transmitted to secondary mixture conduits 18 and 19, when throttles 31 are closed, secondary main nozzle 104 discharges no fuel into secondary mixture conduits 18 and 19.

If, during the warm-up period, primary throttles 29 are fully opened, thus moving extension 116 out of the way of cam 114, spring 121, acting through crank 118, projection 113, and arm 109 will hold secondary throttles 31 closed, since, until the engine is fully warmed up, automatic choke control 27a, acting through choke shaft 26, arm 130, and link 129, opens air vent valve 126, thus killing any suction in bellows 120.

As soon as the engine is warmed up, however, automatic choke control 27a closes vent valve 126 so that vacuum from the Venturi section of the primary mixture conduits is transmitted to bellows 120, causing link 124 to draw arm 118 clockwise in opposition to torsion spring 119 and coil spring 121, unless and until primary throttles 29 are sufficiently opened to move arm extension 116 out of the way of cam 114, as shown in Fig. 4. When this occurs, torsion spring 119 causes projection 113 and arm 109 to follow crank 118, thus opening secondary throttles an amount proportional to Venturi vacuum in the primary mixture conduits. The additional fuel necessary for high-speed or full throttle operation will thus be drawn from bowl 38, through orifice 98, passages 99 and 103, and nozzle 104, into secondary mixture conduits 18 and 19, and thence into intake manifolds 35 and 36, to be added to the fuel supplied by primary mixture conduits 16 and 17.

The exclusive use of all modifications of my invention as come within the scope of the appended claims is contemplated.

I claim:

1. In combination with an internal combustion engine having two intake manifolds, a carburetor having a primary set of mixture conduits for providing a fuel mixture for low and medium speed operation, a second set of mixture conduits for providing additional fuel for high speed operation, throttle valves in each of said mixture conduits, the throttle valves in said primary conduits being manually controlled, the throttle

valves in said secondary mixture conduits being responsive to suction in said primary mixture conduits, separate fuel reservoirs, each fuel reservoir being connected to one primary and one secondary mixture conduit, one primary and one secondary mixture conduit communicating with each intake manifold.

2. In combination with an internal combustion engine having intake manifolds, a carburetor having a primary set of mixture conduits for providing a fuel mixture for low and medium speed operation, a second set of mixture conduits for providing additional fuel for high speed operation, throttle valves in each of said mixture conduits, the throttle valves in said primary mixture conduits being manually controlled, the throttle valves in said secondary mixture conduits being responsive to suction in said primary mixture conduits, and mechanical means associated with the throttles in said primary mixture conduits for preventing opening of said throttles in said secondary mixture conduits until said throttles in said primary mixture conduits have opened a predetermined amount, and thermostatic means for preventing opening of said throttles in said secondary mixture conduits until the engine has warmed up.

3. In a carburetor for internal combustion engines, a primary set of mixture conduits for providing a fuel mixture for low and medium speed operation, a secondary set of mixture conduits for providing additional fuel for high speed operation, thermostatically controlled choke valves for governing the admission of air to said primary and secondary mixture conduits, manually controlled throttle valves for regulating the discharge of fuel mixture from said primary mixture conduits, throttle valves responsive to manifold suction for regulating the discharge of fuel mixture from said secondary mixture conduits, and means responsive to engine temperature for preventing opening of said secondary throttle valves until a predetermined engine temperature is reached.

4. In a carburetor for internal combustion engines, a primary set of mixture conduits for providing a fuel mixture for low and medium speed operation, a secondary set of mixture conduits for providing additional fuel for high speed operation, thermostatically controlled choke valves for governing the admission of air to said primary and secondary mixture conduits, manually controlled throttle valves for regulating the discharge of fuel mixture from said primary mixture conduits, throttle valves responsive to manifold suction for regulating the discharge of fuel mixture from said secondary mixture conduits, two constant level fuel reservoirs, passage means including a main fuel nozzle connecting each reservoir with one primary and one secondary mixture conduit, additional passage means connecting each reservoir with one primary mixture conduit adjacent said throttle valve and means responsive to engine temperature for preventing opening of said secondary throttle valves until a predetermined engine temperature is reached.

5. In a carburetor for internal combustion engines, a primary set of mixture conduits for providing a fuel mixture for low and medium speed operation, a secondary set of mixture conduits for providing additional fuel for high speed operation, thermostatically controlled choke valves for governing the admission of air to said primary and secondary mixture conduits, manually

controlled throttle valves for regulating the discharge of fuel mixture from said primary mixture conduits, throttle valves responsive to manifold suction for regulating the discharge of fuel mixture from said secondary mixture conduits, two constant level fuel reservoirs, passage means including a main fuel nozzle connecting each reservoir with one primary and one secondary mixture conduit, additional passage means connecting each reservoir with one primary mixture conduit adjacent said throttle valve, pump means associated with said reservoirs and adapted to discharge additional fuel into said primary mixture conduits during acceleration, and an operative connection between said pump means and said primary throttles and means responsive to engine temperature for preventing opening of said secondary throttle valves until a predetermined engine temperature is reached.

6. In combination with an internal combustion engine having intake manifolds, a carburetor including a primary set of mixture conduits for providing a fuel mixture for low and medium speed operation, a secondary set of mixture conduits for providing additional fuel for high speed operation, manually controlled throttle valves for regulating said primary mixture conduits, suction responsive throttle valves for regulating said secondary mixture conduits, means responsive to increased suction in the primary mixture conduit for opening said secondary throttle valves, passage means connecting said suction responsive means and said primary mixture conduits, valve means in said passage means communicating with the atmosphere, and thermostatic means for closing said valve means when engine temperature reaches a predetermined value.

7. In combination with an internal combustion engine having intake manifolds, a carburetor having primary mixture conduits for providing a fuel mixture for low and medium speed operation, secondary mixture conduits for providing additional fuel for high-speed operation, choke valves regulating the admission of air to said mixture conduits, a thermostatic choke control

device manually controlled throttle valves in said primary conduits, suction responsive throttle valves in said secondary conduits, a suction responsive bellows for opening said secondary throttle valves responsive to decreases in suction in the primary conduits, a passage connecting said bellows and said primary conduits, a valve in said passage communicating with atmosphere, an operative connection between said valve and said thermostatic choke control device for closing said valve when a predetermined engine temperature is reached.

8. In an internal combustion engine, a carburetor having a primary mixture conduit for providing fuel for low and medium speed operation and a secondary mixture conduit for providing fuel for high speed full throttle operation, metered means for providing fuel to said conduits, a throttle valve in each of said conduits, manual means for controlling said primary throttle, a suction responsive device for controlling said secondary throttle, passage means connecting said suction responsive device with said primary mixture conduit, valve means connecting said passage means with atmosphere, thermostatic means for closing said valve means at a predetermined engine temperature, and mechanical means associated with said primary throttle for locking said secondary throttle until said primary throttle is opened a predetermined amount.
